UNITED STATES PATENT OFFICE.

THOMAS A. SMITH, OF AUSTIN, MINNESOTA, ASSIGNOR TO GEO. A. HORMEL & COMPANY, OF AUSTIN, MINNESOTA, A CORPORATION OF MINNESOTA.

APPARATUS FOR BREAKING ANIMALS' NECKS.

Application filed April 23, 1928. Serial No. 272,105.

This invention relates to an improved apparatus for breaking the necks of animals, particularly hogs, subsequent to the killing of the animal and to facilitate severing the head from the body.

The primary object of the invention is to provide a neck breaking apparatus by means of which the operation, usually requiring two men, can be performed by one with a minimum of time and effort.

A further object of the invention is to provide an apparatus for breaking hogs' necks, comprising a plunger, preferably fluid-operated, having means adapted to engage the hog's neck, a member adapted to engage a jaw of the hog, and means being provided for introducing a pressure fluid against the plunger, whereby the hog's head may be suddenly thrust backwardly and its neck broken.

A further object of the invention is to provide an apparatus of the class described, comprising a barrel having a spring-actuated plunger operable therein and provided at one end with a saddle adapted to engage the back of the hog's neck, a loop adapted to engage a jaw of the animal, and spaced from said saddle and fixed with respect to the barrel, and a fluid control device being connected with the barrel and having a connection with a source of fluid pressure whereby, when said device is operated, fluid will be introduced into the barrel to actuate the plunger and the hog's head will be suddenly thrust backwardly and its neck broken.

Other objects of the invention reside in the constructional details of the apparatus, including the fluid-actuated plunger and the saddle provided thereon for engaging the hog's neck; the demountable loop adapted to engage a jaw of the hog and its connection with the plunger barrel; the general construction of the fluid gun provided for controlling the introduction of a pressure fluid into the barrel to actuate the plunger, and, which also provides means for releasing the fluid from the barrel, to permit the plunger to return to its normal position; and, in the general construction of the apparatus, as a whole.

The particular object of the invention therefore, is to provide an improved fluid-pressure operated apparatus for breaking

hogs' necks, to facilitate the operation of severing the head from the body.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the accompanying drawings forming part of this specification;

Figure 1 is a side elevation of the improved apparatus, partially broken away to show the general construction thereof;

Figure 2 is a plan view of Figure 1, partially in section;

Figure 3 is a view, illustrating the application of the apparatus to a hog's neck and jaw;

Figure 4 is a view similar to Figure 3, showing the plunger operated to break the hog's neck;

Figure 5 is an enlarged detailed sectional view on the line 5—5 of Figure 2; and

Figure 6 is a detailed sectional view on the line 6—6 of Figure 5.

The novel apparatus featured in this invention comprises a barrel 2 having a plunger 3 mounted therein. A piston 4 is secured to one end of the plunger 3 and is normally positioned as shown in Figures 1 and 2. The opposite end of the plunger projects through the end of the barrel 2, and has a saddle 5 secured thereto by such means as a bolt or rivet 6. This saddle is preferably curved as shown in Figure 2 and has a plurality of sharp points 7 provided thereon adapted to pierce the flesh near the jaw, to prevent slippage of the saddle 5, when the plunger is operated. A suitable compression spring 8 is coiled about the plunger 3 and has one end seated against the piston 4 and its opposite end against a shoulder 9, provided at the opposite end of the barrel 2. A slot 11 is preferably provided in the wall of the plunger 3 adapted to receive the terminal 12 of a suitable screw 13, to prevent the plunger from relatively rotating within the barrel 2.

A bracket 14 has one end secured to the barrel 2, as shown in Figure 1, and has its opposite end connected with a member 15 to which a loop 16, preferably of metal, is 5 demountably secured by suitable bolts 17 and nuts 18, shown particularly in Figure 1. The member 15 has an angled seat 19 adapted to receive the loop 16. By reference to Figures 1, 3, and 4, it will be noted that the 10 loop 16 is spaced from the saddle 5, and that it is fixedly secured to the barrel 2 by means of the bracket 14, the upper end 21 of which encircles the end of the barrel 2, as shown. The screw 13 prevents relative movement of 15 the bracket 14 upon the barrel 2. The opposite end of the loop-supporting member 15 is suitably secured to the casing of a fluid-control gun 22, by suitable bolts 23.

The fluid gun 22 has a flange 24 seated 20 against a flanged cap 25, received in threaded engagement with the end of the barrel 2, as shown in Figures 1 and 5. Bolts 26 secure the air gun to the flanged cap 25 of the barrel 2.

The flanged cap 25 has a bore 27 communicating with a bore 28 provided in the air gun 22. These two aligned bores provide a valve chamber adapted to receive a valve 29. The valve is slidable in the valve chamber and has a stem 31 passing through a partition 32 and into a chamber 33, shown in Figure 5. A collar 34 is secured to the stem 31 and has a spring 35 seated against one side thereof, the opposite end of which is seated against the partition 32. This spring 36 constantly urges the plunger 29 in a direction away from the barrel 2, or into its normal position shown in Figure 2. A plug 36 is received in threaded engagement with the end of the bore 33 and is adapted to be engaged 40 by the adjacent end of the stem 31, when the spring 35 moves the stem to its normal position shown in Figure 2.

The valve 29 has an annular groove 37 as shown in Figures 5 and 6. A duct 38 has one 45 end communicating with the valve chamber 28 and its opposite end connected with a port 39, the opposite end of which communicates with a fitting 41 adapted to have a flexible connection 42 connected therewith as shown 50 in Figure 1. This flexible connection leads to a suitable source of fluid pressure, not shown. A duct 43 has one end communicating with the interior of the barrel 2 and its opposite end connected with the valve chamber 28, at a point substantially in alignment 55 with the port 43, shown in Figures 5 and 6. When the valve 29 is in normal position, as shown in Figure 2, communication between the duct 38 and port 43 will be cut off 60 because of the wall portion 44, shown in Figure 6, separating the duct and port from each other, when the valve is in normal position. When the valve is in the position shown in Figure 5, the annular groove 37 will 65 be substantially aligned with the duct 38 and

port 43, thereby establishing communication between the duct 38 and port 43 with the result that the pressure fluid will be admitted to the barrel to operate the piston 4, as will readily be seen by reference to Figures 2 70 and 5.

The means provided for operating the valve 29 consists preferably in a trigger 45, pivoted at 46 to the body of the gun and having forked arms 47, straddling the body of the gun as particularly shown in Figure 6. Links 48 are pivotally connected with the arms 47 and have a pin 49 terminally mounted therein which passes through the body of the fluid gun and through an aperture provided at the end of the valve stem 31. Slots 51 are provided in the body of the air gun to permit movement of the pin 49 when the trigger 45 is actuated.

An exhaust port 52 is provided in the handle 53 of the fluid gun 22, and has one end connected with the valve chamber 28, as shown in Figure 5. The connection between the exhaust port 52 and the valve chamber 28 is such that when the valve 29 is in the position shown in Figure 2, the end of the valve will clear the intake end of the exhaust duct 52 so as to permit the fluid in the barrel to escape therefrom through the exhaust port to the atmosphere. Figure 2 illustrates the 95 valve in its normal position, wherein it will be noted that the exhaust port is open and the intake port is closed.

In describing the operation of this novel apparatus, it is to be understood that the 100 dressed bodies of the hogs or animals are suspended from the usual dressing rail commonly employed in packing plants, with their heads normally positioned substantially as indicated in Figure 3. The purpose of the 105 apparatus is to separate the base of the skull from the spinal column so that the operation of severing the head from the body may be expedited. To break the neck of a hog as above stated, the apparatus is applied to the 110 animal as shown in Figure 3, with the loop 16 preferably inserted in the hog's mouth and the saddle 7 seated against the neck or base of the skull as shown. The apparatus is manually held by the operator, who then pulls the 115 trigger 45 from the position shown in Figure 1, to that shown in Figure 5, thereby opening the valve 29 to permit the pressure fluid to enter the barrel 2 against the piston 4, whereupon the latter is instantly forced 120 forwardly, resulting in the hog's head being thrust backwardly as indicated in Figure 4, causing the breaking of the hog's neck or the separation of the spinal column from the base of the skull. As soon as the trigger is released, the spring 35 will return the valve to its normal position shown in Figure 2, thereby closing the intake port 38 and subsequently opening the exhaust port 52, resulting in the spring 8 returning the piston 4, and there- 130

fore the plunger 3 to their normal positions, shown in Figures 1 and 2.

It has been found that by the use of this novel apparatus for breaking hogs' necks in packing plants and similar places, that the neck-breaking operation is greatly expedited and simplified, and the base of the skull is also separated from the spinal column to the extent that the operation of severing the head from the body is greatly simplified and the head may be removed with a minimum of jowl, as compared to present methods now employed. In large packing plants, where thousands of hogs are slaughtered daily, the use of this apparatus has been found indispensable because of the ease and rapidity with which it may be operated, which allows the operator ample time to break the neck of each hog as it passes his station, suspended from the dressing rail or tracks.

In various ways, the details of construction herein shown and described may be modified and still be within the scope of my invention.

25 I claim as my invention:

1. A hog neck breaking device comprising means adapted to engage a jaw of the dressed hog at right angles substantially to the animal's spine, and means for suddenly applying 30 a thrusting pressure to the neck adjacent said jaw, against the resistance of said jaw-engaging means.

2. A hog neck breaking device comprising means adapted to engage a jaw of the dressed 35 hog at right angles substantially to the animal's spine, and a fluid-operated plunger for applying a thrusting pressure to the neck adjacent said jaw, against the resistance of said jaw-engaging means.

40 3. An apparatus for breaking animals' necks including a fluid-operated plunger, means on said plunger adapted to engage the animal's neck, a member adapted to engage a jaw of the animal, and means for introducing 45 a pressure fluid against said plunger to actuate the latter, whereby the animal's head will be thrust backwardly to break its neck.

4. An apparatus for breaking animals' necks, comprising a barrel having a plunger 50 operable therein, means on said plunger adapted to engage the animal's neck, a member adapted to engage a jaw of the animal, spaced from said means and fixed with respect to said barrel, and means for introducing 55 a pressure fluid against said plunger to actuate the latter, whereby the animal's head will be suddenly thrust backwardly to separate the base of the skull from the spinal column.

60 5. An apparatus for breaking dressed hogs' necks, comprising a barrel having a plunger operable therein, a saddle secured to one end of said plunger and adapted to engage the hog's neck, a member adapted to engage a jaw 65 of the hog, spaced from said saddle, and fixed

with respect to said barrel, and means for introducing a pressure fluid into said barrel to suddenly actuate the plunger, whereby the hog's head will be thrust backwardly and its neck broken.

6. An apparatus for breaking dressed hogs' necks, comprising a barrel having a plunger operable therein, a saddle secured to one end of the plunger and adapted to engage the hog's neck, a loop adapted to engage a jaw of the hog, spaced from said saddle, and fixed with respect to said barrel, and a fluid gun secured to the barrel and having a connection with a source of fluid under pressure and adapted to control the introduction of fluid into said barrel to actuate said plunger.

7. An apparatus for breaking dressed hogs' necks, comprising a barrel having a plunger operable therein, means on one end of said plunger adapted to engage the hog's neck, a supporting member secured to said barrel, a loop demountably secured to said supporting member and adapted to engage a jaw of the hog, and means for introducing a pressure fluid against said plunger to actuate the latter, whereby the hog's head will be thrust backwardly and its neck broken.

8. An apparatus for breaking hogs' necks, comprising a barrel having a spring-retained plunger operable therein, one end of which projects from said barrel, means on the projecting end of said plunger adapted to engage the hog's neck, a supporting member secured to the barrel and having one end spaced therefrom, a member secured to said supporting member and adapted to engage a jaw of the animal, and means for introducing a pressure fluid against said plunger to project it from the barrel, whereby the animal's head will be suddenly thrust backwardly and its neck broken at the base of the skull.

9. An apparatus for breaking hogs' necks, comprising a barrel having a spring-retained plunger operable therein, a saddle secured to one end of said plunger and adapted to engage the hog's neck, a loop adapted to engage a jaw of the hog, spaced from said saddle, and fixed with respect to said barrel, and a fluid control gun secured to one end of said barrel and connected with a source of fluid supply under pressure, and adapted to control the flow of pressure fluid to and from said barrel to actuate the plunger.

10. An apparatus for breaking hogs' necks, comprising a barrel having a plunger operable therein, and provided at one end with a piston, a saddle secured to the opposite end of the plunger and adapted to engage the hog's neck, a spring coiled about said plunger and constantly urging it in one direction, a supporting member secured to said barrel and having one end spaced therefrom, a loop demountably secured to said member and adapted to engage a jaw of the hog, said loop being spaced from said saddle, and a fluid gun se-

cured to the barrel and having a connection with a source of fluid under pressure and adapted to control the flow of fluid to and from said barrel to actuate said plunger, said 5 loop-supporting member having one end secured to the body of said fluid gun.

11. A device for breaking the necks of dressed hogs, comprising a member, adapted

to receive a jaw of the hog, and power-operated means adapted to engage the neck of the 10 animal and to exert a thrusting blow thereagainst, whereby the neck of the animal is broken.

In witness whereof, I have hereunto set my hand this 16th day of April, 1928.

THOMAS A. SMITH.
